[57] CLAIM

The ornamental design for a compact disk player, as shown and described.

DESCRIPTION

FIG. 1 is a perspective view of the top, front and right side of a compact disk player showing my new design; FIG. 2 is a perspective view similar to FIG. 1 with the access door in the open position;

FIG. 3 is a front elevational view of FIG. 1;

FIG. 4 is a rear elevational view thereof;

FIG. 5 is a right side view thereof;

FIG. 6 is a left side view thereof;

FIG. 7 is a top plan view thereof; and,

FIG. 8 is a bottom plan view thereof.

The undisclosed details of the insides of the compact disk player form no part of the claimed design.
